(57) **CLAIM**

The ornamental design for an eyeglasses case, as shown and described.

DESCRIPTION

FIG. 1 is a front perspective view of an eyeglasses case according to a first embodiment of our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof;

FIG. 8 is a front perspective view thereof shown in a manner of use with additional unclaimed environmental features;

FIG. 9 is a front perspective view of an eyeglasses case shown closed in an alternate position of use;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top view thereof; and,

FIG. 15 is a bottom view thereof.

The features shown in broken lines are environmental only and form no part of the claimed design.

1 Claim, 10 Drawing Sheets
